UNITED STATES PATENT OFFICE.

HARRIE A. BALLARD, OF BOSTON, MASSACHUSETTS, ASSIGNOR TO THE PHONOHARP COMPANY, OF EAST BOSTON, MASSACHUSETTS, A CORPORATION OF MAINE.

PLAYING ATTACHMENT FOR ZITHERS.

1,314,117.

Specification of Letters Patent. Patented Aug. 26, 1919.

Application filed November 27, 1917. Serial No. 204,155.

To all whom it may concern:

Be it known that I, HARRIE A. BALLARD, a citizen of the United States, residing at Boston, in the county of Suffolk and State 5 of Massachusetts, have invented new and useful Improvements in Playing Attachments for Zithers, of which the following is a specification.

This invention has relation to stringed 10 musical instruments of the nature of harps or zithers, and it has for its object to provide an improved playing attachment therefor, by which the spring hammers may be actuated and caused to vibrate against the 15 strings and may be held against vibration when normally at rest.

As embodied in the two forms of playing 20 attachments illustrated upon the drawings, the spring hammers are connected to actuating members which are pivoted to move about an axis transverse to the strings, and in coöperative relation to each member there is an elongated stop which extends lengthwise of the hammer but between it 25 and the associated string. When the hammer is at rest in an inactive position, the stop engages the free end thereof and holds it against vibration, but, when the actuating member is actuated to impel the hammer head toward its associated string, the stop 30 is moved to an inactive position where it does not interfere with the free vibration of the hammer head. The elongated stop may 35 constitute an integral part of the hammer actuating member or it may be formed separately so as to be capable of movements relatively thereto.

Referring to said drawings,—

Figure 1 represents in plan view one end 40 of a zither provided with a playing attachment embodying my invention.

Fig. 2 is a plan view partially in section of several hammers and actuating members, two of the hammers being broken off for 45 purposes of illustration.

Fig. 3 shows in section the end of the zither body, and certain of the hammers and actuating members. One of the members and the associated hammer are shown with 50 the hammer vibrating against the string.

Fig. 4 illustrates a longitudinal section on the line 4—4 of Fig. 2.

Fig. 5 illustrates an end wall of the support.

Fig. 6 illustrates one of the spacers.

Figs. 7 to 12 inclusive show another embodiment of the invention, Fig. 7 illustrating a portion of the zither and the playing attachment in plan view. Figs. 8 and 9 show in plan and in side elevation several 60 of the hammers and their associated actuating members. Fig. 10 represents a vertical section through one of the hammers and its actuating member. Figs. 11 and 12 illustrate respectively an end wall and a spacer 65 of the support.

The stringed instrument, which I have selected for illustration as being one of those on which the attachment may be used, is a zither formed in the usual way and 70 provided with a group of melody strings 20 and a plurality of groups 21 of chord strings. There may be two melody strings for each tone, as shown, but for simplicity I shall refer to them as though there were 75 but one string associated with each hammer.

The attachment includes a support formed in any suitable manner so that it may be secured to the body of the zither, preferably to the straight end thereof. Said 80 support may comprise the end walls 22, a top wall 23, a bottom wall 24, and an exterior metal casing 25. The support projects above the plane of the strings and its top wall may project far enough to overlie 85 the bridgewire 26 and a portion of the strings. Spacers 27 are employed and they are glued or otherwise fastened in the support, and they may be shaped as shown in Fig. 6, or at intervals these may be replaced by spacers 28 which are shaped like 90 the end walls to form intermediate supports for one of the cross rods to be described.

Each of the spring hammers comprises a leaf spring shank 29 and a head 30 of wood 95 or metal at the free end thereof. The actuating member 31 therefor is shown as a hollow bar formed of sheet metal, bent to provide a top wall and parallel side walls. The bottom wall is formed by a flat bar 32 which 100 projects forwardly from the ends of the top and side walls, and which is secured between the margins of the side walls by suitable fastenings 33. The actuating member thus consists of a tube which is rectangular in 105 cross section. Each member is mounted to move above a pivot 34 arranged transversely above the strings and supported by the end walls and the spacers of the support. The pivot may consist of a rod or wire as shown. 110

The movement of the actuating members about their pivot is limited by a cross wire or rod 35 supported by the end walls and the spacers 28, and curved slots 36 formed in the side walls of said members. The rear portion of each hammer shank extends through the associated tubular actuating member, and its extremity is secured in a clip 37 formed on the end of the top wall. 10 The clip 37 extends upwardly and rearwardly and the rear end of the hammer shank is consequently bent so as to cause the middle portion of the shank to rest upon the bottom wall of the actuating member. The 15 springs are all above the cross wire or rod 35 and rest thereon, the resiliency of the springs being sufficient, in view of the arrangement thus described, normally to cause the actuating members to remain at rest with 20 the hammers above their associated strings and at an acute angle thereto.

The bar 32 extends forwardly to a point adjacent the head of the associated hammer, and its upper surface is provided with a 25 strip 137 of felt or other cushioning material, and it serves as a stop to prevent the vibration of the hammer head when the actuating member, after having been operated, is released and returned to its angular 30 position.

The player, in operating a hammer, depresses the actuating member 31 from the inclined position to the horizontal position shown in Fig. 3. During the initial downward movement of said member about its 35 pivot 34, the shank of the hammer is prevented from swinging downwardly by the cross wire 35, but, when the top wall of the actuating member engages the shank of the 40 hammer, it forces it downwardly and impels the head of the hammer against the string. When the actuating member comes to a state of rest, the stop bar 32 is in the horizontal position shown in Fig. 3, wholly out of contact with the hammer so as to permit the 45 hammer to vibrate against its associated string. When the player releases the actuating member, the pressure of the rear portion of the shank of the hammer upon the 50 cross wire or rod 35 returns the member to its initial inactive position and the elongated stop member engages the hammer shank and holds it from vibrating. The end of the top wall of the actuating member defines the node of vibration of the free end 55 of the shank of the hammer, as indicated in dotted lines in Fig. 3.

Referring now to Fig. 7 to 12 inclusive, another embodiment of the invention is 60 illustrated in which the stop bar is movable about a pivot separate from that about which the actuating member is moved, and a separate spring is utilized for returning the actuating member and the spring hammer to their normal positions. The actuat-

ing member is indicated as a whole at 40, and it is provided at its rear end with depending ears 41 which are mounted upon a pivot 42, consisting of a rod or wire supported by end walls 43 and certain of the 70 spacers which constitute a portion of the support. The actuating member may be made of metal and the body portion thereof is tubular in form and substantially rectangular in cross section. The shank of the 75 hammer 44 is secured in clips 45, 46, formed at the ends of the actuating member. A spring 47, having one end engaging the under side of the body of the actuating member and its other end secured to the 80 support, tends to hold the actuating member and the hammer in thin normal position at an acute angle to the associated string and with the hammer head relatively remote from the said string. The spring 47 crosses 85 the pivot 42 and lies between the ears 41 of the actuating member. The support does not differ materially from that described in connection with the first embodiment of the invention, and it comprises the front 90 wall 147, top wall 48, bottom wall 49, end walls 43, and spacers 50, 51. An inclosing casing of metal 52 is employed as in the attachment first herein described. The springs 47 may be secured to a block 53 formed on 95 or secured to the inner face of the front wall 147 by a bar 54. If desired, however, the ends of the springs may be secured in any other suitable way, as by means of a cast metallic strip. 100

The oscillatory movement of each actuating member is limited by a cross rod or wire 55, passing through curved slots 56 in the ears 41 and supported by the end walls and spacers of the support. 105

The stop bar, which holds the hammer from vibrating when the actuating member is in its normal position, is indicated as a whole at 57. It passes through the tubular body of the actuating member and its rear end is pivoted upon the rod or wire 55. The free end of the stop bar is provided with a strip 58 of felt or other cushioning material upon its upper face for engagement with the head of the hammer. The pivot 110 42 is in a horizontal plane below the plane of the pivot rod or wire 55, and in a vertical plane relatively remote from the vertical plane of the pivot rod 55. Consequently, when the actuating member is depressed about the pivot 42, the hammer is advanced longitudinally relatively to the stop 57, so that the head eventually clears the end of said stop. If desired, the stop may be provided with a cam or wedge projection 59, 115 on which the end of the actuating member will ride so as to depress the free end of the stop member relatively to the free end of the hammer, as indicated in Fig. 9, the tubular body of the actuating member be- 120 130

- ing sufficiently large to permit the relative swinging movement of the stop. Assuming that the actuating member and the hammer are in their normal raised positions, when 5 the actuating member is depressed by the finger of the player, it is swung about the pivot 42, and, as it moves downwardly, the stop member 57 is moved about its pivot 55, with the result that the hammer head 10 is projected beyond the end of the stop and the ends of the hammer and the stop are separated by the engagement of the cam projection 57 with the end of the clip 45. Continued depression of the actuating 15 member throws the hammer head against the associated string, the actuating member coming to a state of rest as soon as the end wall of the slot 56 engages the pivot 55. The free end of the hammer vibrates rapidly against the string and produces a succession of notes, provided the actuating member be held in its depressed position. When the actuating member is released, the spring 47 returns it and the stop 57 to their 20 raised positions, and, as these parts move upwardly, the hammer is retracted relatively to the stop to cause its head to ride up on the end of the stop and rest upon the felt cushion 58. As a result, the hammer is prevented from vibrating when it 25 returns to its normal raised position.
- In both constructions which I have herein illustrated and described, the actuating member is mounted to swing about a pivot 30 and its movement is limited by a cross wire passing through slots formed in the sides of said actuating member. In both constructions, the hammer and the actuating member are returned to inactive position by 35 spring pressure, in one case the rear end of the shank hammer constituting the return spring and in the other case a separate spring as at 47 being employed for the purpose. In both constructions, there is 40 a separate stop associated with each hammer, which underlies the hammer and which is moved to an inactive position in respect of the hammer when the actuating member is depressed, and which automatically engages the hammer when the actuating 45 member is released, to prevent vibration thereof.
- It is quite evident that the herein described invention is capable of various other 50 embodiments and that various changes may be made in the details of the structure which I have herein described without departing from the spirit and scope of the invention as defined in the claims. While 55 I have illustrated the attachment as being more especially useful in playing the melody strings of the zither, it is quite apparent that it also may be employed for playing the chord strings. The supports of the two 60 actions, which I have herein described, are 65 illustrated as being made of wood and inclosed within a metallic casing, but of course it will be understood that these supports may be made in any suitable way so as to hold the cross wires or pivots in the 70 desired positions, and, to secure the proper spacing of the actuating members and the associated hammers in the present case, the supports may be secured to the end of the zither body by fasteners of any suitable 75 kind, this being a feature of detail which needs no explanation.
- Having thus explained the nature of my said invention and described a way of making and using the same, although without 80 attempting to set forth all of the forms in which it may be made or all of the modes of its use, what I claim is:
1. A playing attachment for zithers, comprising a plurality of spring hammers, and a plurality of relatively movable stops associated with and underlying the hammers and normally holding the free ends of said hammers from vibrating. 85
  2. A playing attachment for zithers, comprising a plurality of spring hammers, a plurality of relatively movable stops associated with and underlying the hammers and normally holding the free ends of said hammers from vibrating when in their inactive 90 positions, and means for moving each stop, independently of the others, to permit the associated hammer to vibrate. 95
  3. A playing attachment for zithers, comprising a plurality of spring hammers, an actuating member associated with each hammer, and a stop associated with each member beneath the associated hammer and normally holding the free end of the said hammer from vibrating. 100
  4. A playing attachment for zithers, comprising a plurality of spring hammers, a plurality of pivoted actuating members, a pivot for said members, and a plurality of stops projecting from said members beneath the hammers and normally holding the free ends of said hammers from vibrating. 110
  5. A playing attachment for zithers, comprising a plurality of spring hammers, a plurality of pivoted actuating members, a pivot for said members, a plurality of stops projecting from said members beneath the hammers and normally holding the free ends of said hammers from vibrating, and means for limiting the movement of said members about said pivot. 115
  6. A playing attachment for zithers, comprising a plurality of spring hammers, a plurality of actuating members to which the rear ends of the hammers are respectively secured, a pivot on which said members are pivoted, and a stop associated with each actuating member underneath the associated hammer and movable to inactive position on the actuation of said member. 120

7. The combination with a zither, of a playing attachment comprising a plurality of spring hammers associated with and normally at an acute angle to the several strings, and a plurality of stops located between the hammers and the strings and normally engaging the free ends of the hammers and holding them from vibrating.

8. The combination with a zither, of a playing attachment comprising a plurality of spring hammers associated with and normally at an acute angle to the several strings, a plurality of stops located between the hammers and the strings and normally engaging the free ends of the hammers and holding them from vibrating, and means for depressing each stop to release the associated hammer and permit its vibration.

9. The combination with a zither, of a playing attachment comprising a plurality of spring hammers associated with and nor-

mally at an acute angle to the several strings, a plurality of stops located between the hammers and the strings and normally engaging the free ends of the hammers and holding them from vibrating, and a plurality of hammer-actuating members associated with said hammers and said stops and operable to actuate said hammers and to move said stops to inactive positions.

10. The combination with a zither, of a playing attachment comprising a plurality of spring hammers associated with and normally at an acute angle to the several strings, a pivot about which said hammers are movable, and a plurality of stops associated with said hammers and located between the hammers and the strings and relatively movable about a pivot.

In testimony whereof I have affixed my signature.

HARRIE A. BALLARD.
